(57) **CLAIM**

The ornamental design for a tabletop cigarette making machine, as shown and described.

DESCRIPTION

FIG. 1 is a front perspective view of the tabletop cigarette making machine;

FIG. 2 is a right side elevation view of the tabletop cigarette making machine of FIG. 1;

FIG. 3 is a left side elevation view of the tabletop cigarette making machine of FIG. 1;

FIG. 4 is a front elevation view of the tabletop cigarette making machine of FIG. 1;

FIG. 5 is a rear elevation view of the tabletop cigarette making machine of FIG. 1;

FIG. 6 is a top plan view of the tabletop cigarette making machine of FIG. 1; and,

FIG. 7 is a bottom plan view of the tabletop cigarette making machine of FIG. 1.

The broken lines shown in the figures illustrate portions of the tabletop cigarette making machine that form no part of the claimed design.
